ALARM APPARATUS

George F. Blethen, Corpus Christi, Tex.

Application July 23, 1940, Serial No. 347,023

5 Claims. (Cl. 274—9)

This invention relates to signal or alarm apparatus, one of the objects being to provide a structure which, upon the closing of an electric circuit, will operate to pick up a recorded message and transmit it by short wave broadcasting apparatus so that the message can be picked up by the police or other authorities within a reasonable distance.

A further object is to provide apparatus of this character which can be installed readily and includes, in addition to a rotatable record holder, a means for automatically applying a pick-up device to the rotating ratchet and subsequently lifting it therefrom and restoring it to its normal position at which time all working parts of the apparatus following transmission of the message, will be reset ready for further use.

A still further object is to provide an apparatus especially adapted for use in banking institutions and other places where it is desired to send out a call for assistance in emergencies. With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawings the preferred form of the invention has been shown.

In said drawings:

Figure 1 is a central vertical section through the apparatus, the only portion of the electric circuit illustrated therein being some of the contacts.

Figure 2 is a plan view of the structure shown in Figure 1, the said contacts and their housing being removed.

Figure 3 is a plan view of the motor and adjacent parts, said view being a section on line 3—3, Figure 1.

Figure 4 is a section on line 4—4, Figure 1.

Figure 5 is a view similar to Figure 4 but showing the lever held in lowered position by the clutch arm.

Figure 6 is a section on line 6—6, Figure 1.

Figure 7 is an enlarged longitudinal section through one of the controlling switches of the apparatus.

Figure 8 is a view showing the complete apparatus in diagram.

The apparatus includes a casing 10 in which is journaled a vertical shaft 11 extending 55

through the top of the casing and provided with a turntable 12 for supporting a record 13. This record, which is of the disk type, has a track groove 14 the convolutions of which are more widely spaced than ordinarily and slightly deeper than the usual groove, these grooves containing recordings of a message adapted to be repeated one or more times. For example the message can be a call for police to come to a particular address.

Mounted in the casing 10 is an electric motor 15 having an armature shaft 16 to which is keyed or otherwise secured a ratchet wheel 17. This ratchet wheel is normally engaged by a spring-pressed pawl 18 mounted on one side of a gear 19 which is loosely rotatable on shaft 16. The parts are so positioned that when the armature shaft is rotating in one direction, the ratchet wheel will drive through the pawl 18 to the gear 19. When the armature shaft is rotated in the opposite direction, however, the pawl 18 will be shifted out of engagement with the ratchet teeth and gear 19 will remain stationary.

Gear 19 meshes with an intermediate gear 20 secured to a counter-shaft 21 which, in the structure shown, is adapted to transmit motion through chain and sprocket mechanism 22, to a transverse shaft 23 mounted in suitable bearings. By means of gears 24 motion is transmitted from 30 the shaft 23 to the turntable shaft 11.

A friction disk 25 constituting a clutch member is secured to and rotates with the armature shaft 16. Another friction disk 26 constituting the other clutch member, is loosely mounted on 35 the shaft 16 and has a sleeve 27 extending from the center thereof and is slidable and rotatable on the shaft. Surrounding this sleeve and bearing against clutch member 26 is a coiled spring 28 the compression of which can be regulated 40 by means of a nut 29 mounted on the threaded end of shaft 16. This clutch member 26 is held normally pressed against clutch member 25 so that under certain conditions the two members will be caused to move together in one direction.

Extending from the margin of clutch member 26 is an extension 30 from which projects a clutch arm 31 bowed laterally as shown particularly in Figure 1. A coiled spring 32 serves to hold this arm normally inclined upwardly as in Figures 1, 3 and 4 at which time a stop lug 33 projecting from the clutch member is spaced from a stop bracket 34 projecting into the path thereof.

A socket member 35 is fixedly mounted on the housing 10 and constitutes a bearing for the cup-like head 36 of a shank 37 extending down-

wardly into and rotatable within the top of the housing or casing 10. This shank is held in place by nuts 38 and a washer 39 or any other suitable means and has a hanger 40 extending downwardly therefrom and rotatable therewith. A lever 41 is fulcrumed between its ends in the lower end of the hanger 40 when one arm of this lever, indicated at 42, projects into the path of the clutch arm 31 as shown particularly in Figure 4. A coiled spring 43 connects this arm to one wall of the housing or casing 10 and serves to hold lever 41 normally in the position shown in Figures 3 and 4.

The other arm 44 of lever 41 has an adjustable tension spring 45 extending downwardly therefrom and anchored to the casing or housing 10. A connecting rod 46 is pivotally joined to and extends upwardly from the arm 42 through an arcuate slot 47 in the top of the housing 10, this slot being concentric with the shank 37.

Anchored in the head 36 so as to rotate therewith is a stud 48 or the like projecting downwardly from and made integral with a housing 49 which is open at the bottom. In this housing are journaled the end portions of a cross-pin 50 extending through the tubular arm 51 extending from the pick-up device including the usual diaphragm stylus 52 and microphone 53 which latter is electrically connected to a broadcast transmitter indicated generally at 54, this transmitter being preferably of low power so that the area covered thereby would only include that in which are located one or more portable or transmitting stations tuned to the same wave length as the transmitter 53.

A lever 55 is pivotally mounted on the pin 50 and extends beyond one end of arm 51 where it is pivotally engaged by the connecting rod 46. Lever 55 works within a slot 56 in arm 51 so that a limited up and down movement of the lever relative to the arm is permitted.

As will be apparent by referring to the drawings, the spring 43 holds lever 42 normally at one limit of its movement and at this time the spring 45 is extended along a line parallel with the hanger 40. At the same time this spring 45 pulls down on lever 44 with sufficient force to cause lever 55 to press downwardly on the lower end of slot 56 thereby holding the stylus out of contact with the record 13 but close to the outer convolution of the groove 14. When arm 51 is thus supported it transmits thrust through a pin 57 to a resilient contact 58 which is thus held away from another contact 59, the two contacts being insulated from each other and from the pin and also from the housing 49 in which they are fixedly mounted. Likewise when the arm 51 is thus supported with the stylus out of contact with the record, the free end of lever 55, which extends under superposed pairs of contacts, permits the contacts of each pair to be spaced apart as shown particularly in Figure 1. In said figure the contacts of one pair have been indicated at 60 and 61 while the contacts of the other pair have been indicated at 62 and 63. Not only are these contacts normally insulated from the other contacts of the same pair but the two pairs are insulated from each other and also from the lever and it will be apparent by referring to said figure wherein insulating blocks have been indicated at 64 and 65. Block 64 is carried by lever 55 while block 65 is interposed between contacts 61 and 62 and is carried by one of them.

The electrical apparatus forming a part of this

invention has been illustrated in diagram in Figure 8. It includes a starting relay 66 and a holding relay 67. A double armature in the form of a lever 68 is normally spaced from the cores 5 of both relays and has that arm thereof nearest relay 67, normally removed from spaced contacts 69 and 70. Lead-in wires from an outside circuit have been indicated at 71 and 72 and one of them is adapted to be connected through the contacts 69 and 70 when closed, to one side of the motor 15 while the other lead-in wire is connected to the other side of the motor. Included in the apparatus are two transformers indicated at 73 and 74 respectively. Transformer 73 is electrically connected to the starting relay 66 and to one side of a controlling switch 75. In the drawings two of these switches have been shown. It is to be understood that any desired number can be used. As illustrated particularly in Figure 1 each switch includes a stationary contact 76 connected to one side of the transformer while a movable contact 77 is connected to the other side of the transformer. This movable contact is mounted on the stem 78 of a plunger 79 having valved openings 80 and working within a dash-pot 81 containing a suitable liquid 82. A knob 83 or the like is mounted on the exposed end of the stem 78 and a spring 84 is interposed between this knob and the contact 30 77. Obviously when the knob 83 is depressed against the action of the spring 84, contact 77 is brought against contact 76 and a portion of the liquid 82 is displaced upwardly through the plunger. When the plunger is released the spring 35 84 will return it slowly to raised position. Consequently after contact has once been made at 76 and 77, it will not be broken until after a predetermined time interval has elapsed following release of the knob 83.

One side of transformer 73 is also connected to contact 62. Contact 63 is connected to contact 69 while contact 58 is electrically connected to one terminal of the holding relay 67. The other terminal of this holding relay is electrically connected to the other side of the transformer 73.

One side of transformer 74 is electrically connected to contact 61 while contact 62 is electrically connected through a flasher 85 to one 50 side of an electric lamp 86 the other side of which is joined to the other terminal at the low side of the transformer 74. Obviously two or more of these lamps can be connected together in parallel as shown and can be located 55 wherever desired.

Normally the parts are positioned as shown in Figures 1, 3, 4 and 8. When it is desired to broadcast a recorded signal one of the controlling switches 75 is depressed so as to bring contact 77 against contact 76. This promptly closes the circuit to starting relay 66 and when this relay is energized it attracts its armature 68 so that contact 69 will be thrust against contact 70. This closes the circuit to the motor 15 which immediately starts rotating. Motion will be transmitted from shaft 16 through ratchet wheel 17 and pawl 18 to gear 19 and thence through gear 20 and the chain and sprocket mechanism to shaft 23, gears 24 and shaft 11. 60 This will of course result in the rotation of table 12 and the record 13 thereon. As the shaft 16 rotates, the clutch member 25 which moves therewith, instantly picks up the clutch member 26 which is thrust thereagainst. Thus this clutch member 25 is caused to make a quick

movement from the position shown in Figure 4 to the position shown in Figure 5, thereby placing spring 32 under increased tension and depressing the arm 42 of lever 41. The depression of this arm will be sufficient to elongate spring 45 and thrust upwardly through rod 46 against lever 64 thereby closing contact 60 against contact 61 and contact 62 against contact 63. At the same time arm 51 will be relieved from the restraining influence of lever 55 with the result that that end thereof carrying the stylus 52 will move downwardly by gravity until the stylus comes into contact with the record and is seated in the outer convolution of the groove 14. The pick-ups will act to convert the recorded waves into sound which, in turn, will be picked up and transmitted on the predetermined wave lengths. The rotating record will cause the stylus 52 to swing slowly toward the center of the record and as it thus travels, arm 51 will swing therewith about the longitudinal axis of shank 31. This will cause the lever 41 also to move with shank 31 and hanger 40 and at the same time arm 44 will pull against the action of spring 45. Rod 46 will move around within slot 47. When arm 51 gravitated as described, it released the pin 57 so that contact was made at 58 and 59. This resulted in maintaining a closed circuit to the holding relay 67 by way of contacts 62 and 63. Furthermore as contacts 60 and 61 are brought together by lever 55 the circuit to the flasher and the lamp or lamps is closed so that the visible signal thus is operated while the audible signal is being broadcast.

When the clutch arm 31 moves downwardly onto the arm 42 of lever 41 it is held against further downward movement after said arm has been depressed but as there is a slip connection between the two clutch members 25 and 26, shaft 16 can continue to rotate even though clutch member 26 is held against rotation. The frictional contact between these parts will be sufficient to maintain spring 32 under increased tension. As hanger 40 rotates slowly under the action of the stylus 52 in the groove 14, arm 42 gradually moves toward the free end of arm 31 and finally is pulled out from under said arm. As soon as this operation occurs the tensioned spring 45 pulls back on arm 44 so as to simultaneously pull downwardly through rod 46 on lever 55, thereby lifting the stylus 52 out of groove 14 and also rotating hanger 40 and lever 41 to restore the parts to their initial positions. Obviously when this action took place the contacts were instantly restored to their initial positions and as the circuit to the motor was broken, said motor became deenergized. Thus the tension of the spring 32 becomes sufficient to rotate the clutch members 26 and 25 and the shaft 16 in a direction opposite to that in which it was driven when the motor was energized and during this action the ratchet wheel 17 will slip past the pawl 18 so that the gears will not be operated. Thus the clutch member 26 and the arm 31 will be restored to the positions as shown in Figure 4 and the apparatus thus reset to repeat the operation already described.

What is claimed is:

1. Alarm apparatus including a motor, a normally open motor circuit, a rotatable record holder, means for transmitting motion from the motor to said holder, an arm mounted for up and down and lateral swinging movement, sound reproducing means including a stylus normally disengaged from but positioned to engage the

record, a lever mounted for lateral swinging movement with the arm, a connection between the lever and arm, yielding means cooperating with the lever and connection for holding the arm and stylus normally raised from the record, a depressor arm, a friction slip driving connection between the motor and arm, and a spring for holding said arm normally in one position, said arm being positioned to engage the motor-actuated lever and shift it, thereby to release the stylus and its arm for gravitation toward the record.

2. Alarm apparatus including a motor, a normally open motor circuit, a rotatable record holder, means for transmitting motion from the motor to said holder, said means including a pawl and ratchet mechanism, an arm mounted for up and down and lateral swinging movement, sound reproducing means including a stylus normally disengaged from but positioned to engage the record, a lever mounted for lateral swinging movement with the arm, a connection between the lever and arm, yielding means cooperating with the lever and connection for holding the arm and stylus normally raised from the record, a depressor arm, a friction slip driving connection between the motor and arm, and a spring for holding said arm normally in one position, said arm being positioned to engage the motor-actuated lever and shift it, thereby to release the stylus and its arm for gravitation toward the record, said spring and pawl and ratchet mechanism constituting means for driving the motor to return the depressor arm to its normal position and release the lever and stylus arm for return to their normal positions by said yielding means.

3. Alarm apparatus including a motor, a normally open motor circuit, a rotatable record holder, means for transmitting motion from the motor to said holder, an arm mounted for up and down and lateral swinging movement, sound reproducing means including a stylus normally disengaged from but positioned to engage the record, a lever mounted for lateral swinging movement with the arm, a connection between the lever and arm, yielding means cooperating with the lever and connection for holding the arm and stylus normally raised from the record, a depressor arm, a friction slip driving connection between the motor and arm, and a spring for holding said arm normally in one position, said arm being positioned to engage the lever and stylus constituting means for engagement with the record for actuation thereby to swing laterally out of normal position the stylus arm, the lever and the connection therebetween, and to place the yielding means under increased tension.

4. Alarm apparatus including a motor, a normally open motor circuit, a rotatable record holder, means for transmitting motion from the motor to said holder, said means including a pawl and ratchet mechanism, an arm mounted for up and down and lateral swinging movement, sound reproducing means including a stylus normally disengaged from but positioned to engage the record, a lever mounted for lateral swinging movement with the arm, a connection between the lever and arm, yielding means cooperating with the lever and connection for holding the arm and stylus normally raised from the record, a depressor arm, a friction slip driving connection between the motor and arm, and a spring

for holding said arm normally in one position, said arm being positioned to engage the lever and shift it against the action of the spring, thereby to release the stylus and its arm for gravitation toward the record, said spring and pawl and ratchet mechanism constituting means for driving the motor to return the depressor arm to its normal position and release the lever and stylus arm for return to their normal positions by said yielding means, said stylus constituting means for engagement with a record on the holder for actuation thereby to swing laterally out of normal position the stylus arm, the lever, and the connection therebetween, and to place the yielding means under increased tension, said yielding means constituting means for swinging the stylus arm, the lever and their connection laterally in the opposite direction when the stylus is disengaged from the record.

5. Alarm apparatus including a motor, a normally open motor circuit, a rotatable record holder, means for transmitting motion from the motor to said holder, said means including a pawl and ratchet mechanism, an arm mounted for up and down and lateral swinging movement, sound reproducing means including a stylus normally disengaged from but positioned to engage the record, a lever mounted for lateral swinging movement with the arm, a connection between the lever and arm, yielding means co-operating with the lever and connection for holding the arm and stylus normally raised from the record, a depressor arm, a friction slip driving connection between the motor and arm,

10 and a spring for holding said arm normally in one position, said arm being positioned to engage the lever and shift it against the action of the spring, thereby to release the stylus and its arm for gravitation toward the record, said spring and pawl and ratchet mechanism constituting means for driving the motor to return the depressor arm to its normal position and release the lever and stylus arm for return to their normal positions by said yielding means, said stylus constituting means for engagement with a record on the holder for actuation thereby to swing laterally out of normal position the stylus arm, the lever, and the connection therebetween, and to place the yielding means under increased tension, said yielding means constituting means for swinging the stylus arm, the lever and their connection laterally in the opposite direction when the stylus is disengaged from the record, a starting relay, a starting switch included in a circuit with said relay, a holding relay connected to be energized simultaneously with the starting relay, a motor circuit including a normally open switch, said starting relay constituting means for actuating the switch to close the motor circuit and said holding relay constituting means for holding the circuit closed when the starting relay is deenergized, and separate means operated by the stylus arm and the lever and arm connection respectively for deenergizing the holding relay and breaking the motor circuit when the stylus is raised.

GEORGE F. BLETHEN.
